W. WORONIECKI.
RAIL JOINT AND FISH PLATE.
APPLICATION FILED SEPT. 21, 1921.

1,402,130.

Patented Jan. 3, 1922.

UNITED STATES PATENT OFFICE.

WINCENTY WORONIECKI, OF DICKSON CITY, PENNSYLVANIA.

RAIL JOINT AND FISH PLATE.

1,402,130.

Specification of Letters Patent. Patented Jan. 3, 1922.

Application filed September 21, 1921. Serial No. 502,191.

To all whom it may concern:

Be it known that I, WINCENTY WORONIECKI, a citizen of Poland, residing at Dickson City, in the county of Lackawanna and 5 State of Pennsylvania, have invented certain new and useful Improvements in Rail Joints and Fish Plates, of which the following is a specification.

This invention relates to an improved rail 0 joint, and pertains more particularly to the type of fish-plate employed for securing together the abutting sections of rails.

It is the object of the present invention to provide an improved rail joint of simple and 5 durable construction capable of producing a dependable connection between two rail sections.

One feature of the invention relates to the particular construction of both fish- 0 plates of the joint and to the manner in which these plates are fitted together with the peculiar rail ends, and a sturdy supporting member which embraces the fish-plates and rails. To this and other ends the invention consists in the novel features of construction and combinations of elements hereinafter described.

One form of the invention is described and claimed in the following specification 0 and claims and illustrated in the accompanying drawings, in which:

Fig. 1 is a plan view showing a rail joint of the general type of the present invention.

Fig. 2 is a sectional plan view on line 2—2 5 of Fig. 3.

Fig. 3 is a sectional view on line 3—3 of Fig. 1.

In the rail joint illustrated in Fig. 1, the sections of standard T-rail to be joined together are shown at 1 and 2 with the intervening joint 3. For the purposes of this invention there is shown a standard T-rail such as is ordinarily used for railways. The two abutting sections of rail rest upon 5 a base-plate 4 constructed substantially as shown in Figs. 1 and 3.

This base-plate is of such a width as to rest securely upon a tie, not shown in the drawing, and of a length sufficient to give a 0 substantial bearing surface upon a portion of the tie on either side of the rail. In practice, two of these base-plates will be placed upon each tie in the construction of a railway. Upon the upper face of this base- 5 plate, the base of the rail is so placed as to be on the center line and spaced equidistant

from two projecting members 5 and 6, attached to the base-plate. In the drawing they are shown as being cast integral with the base-plate and so shaped as to form 60 parallel inclined tongues or abutments, their purpose being to grip the improved fish-plates 7 and 8 more fully described hereinafter. On the face of the base-plate and disposed at either end thereof are openings 65 10 and 11 through which any suitable fastening devices may be inserted to secure the base-plate to a resting surface or tie.

In the construction of the rail section 1 it will be noticed that on the under surface of 70 the head of the rail a slot or channel 12 has been cut, said slot extending from the longitudinal edge of the head of the rail to the web of the rail, the bottom of the slot being parallel to the surface of the railhead. The 75 slot is more clearly shown at 12 of Fig. 3. On the under surface of the rail head opposite to slot 12 of rail section 1 is a slot 15, said slot being L-shaped, having one end adjacent the longitudinal edge of the rail 80 head and the other end at a substantial distance from the cross-cut end of rail section 1. The bottom of this slot is parallel to the rail head and is of a width adapted to take a projecting pin 19 to be described more 85 fully. The slot is shown at 15 of Fig. 3 and is there more clearly represented.

Rail section 2 has slot 13 constructed in the same manner as slot 12 and slot 14 constructed in the same manner as slot 15, with 90 the exception that one leg of the L-shaped slot is turned away from the cross-cut of rail 2 rather than toward the cross-cut as in rail 1.

The web section 9 of rails 1 and 2 is that 95 of a standard T-rail. In the web of rail section 1 are two openings 20 and 21 which lie in the same horizontal plane on a level corresponding to that of 2—2 of Fig. 3. These 100 openings are of dimensions sufficient to take an L-shaped locking pin 23. Locking pin 24 is of the same dimension as locking pin 23. Likewise in rail section 2 is an opening 22 in the rail web of dimensions sufficient to take an L-shaped locking pin 25 corresponding to the locking pins 23 and 24 of rail section 1. This opening 22 also lies in the same horizontal plane as openings 20 105 and 21 of rail section 1.

In order to connect the two rail sections 110 so as to form a durable joint, I make use of improved fish-plates the general form of

which is shown in Fig. 3 at 7 and 8. For the purposes of description, I shall call fish-plate 7 the primary fish-plate and fish-plate 8 the secondary fish-plate. In cross-section 5 and length both fish-plates are identical but they vary in some details of construction. Both fish-plates conform to the true outline of the rail comprising the under surface of the head of the rail, the web of the rail and 10 the lower portion of the rail. The lower surface of the fish-plate rests securely on the base plate 4. The outer surface of the fish-plate conforms to the shape of the tongue 5. The length of the fish-plate is 15 sufficient to cover a portion of each of the rail sections 1 and 2 adjacent the joint 3. Cast integral with fish-plate 7 is the L-shaped locking pin 24 which protrudes from the inner surface of the fish-plate next to 20 the rail web. The position of this L-shaped pin is best shown at 24 of Fig. 3. In the interior of fish-plate 7 are two L-shaped recesses 26 and 27 of dimensions slightly larger than those of the projecting pins 23 and 25. These recesses are constructed exactly alike and lie in a plane 2-2.

The secondary fish-plate 8 has the same dimensions as those of fish-plate 7 but on its inner surface it has two protruding L-shaped pins 23 and 25 cast integral with the fish-plate and of the same dimensions as those of pin 24. In the interior of fish-plate 8 there is an L-shaped recess 28 of dimensions slightly larger than those of the projecting pin 24. This recess, however, is faced in a direction opposite to the direction of the recesses 26 and 27. Likewise, pin 24 is faced in a direction opposite to the direction of pins 23 and 25. On 30 the upper face of fish-plate 7 are two vertically projecting pins 16 and 17 and on the upper face of fish-plate 8 are two vertically projecting pins 18 and 19.

In assembling the various parts hereinbefore described so as to obtain a rail joint, fish-plate 7 is inserted between the two abutting rail sections 1 and 2 and the tongue 5 of base-plate 4, in the position shown in Fig. 3. The pin 24 therefore projects 45 through opening 21 in the rail-web and pins 16 and 17 are inserted in their respective slots 12 and 13, thereby locking the fish-plate 7 and preventing any longitudinal movement. The secondary fish-plate 8 is 50 slidable and is inserted between the rail sections and tongue 6 as shown in Fig. 3. Before insertion, fish-plate 8 assumes the position of the dotted lines shown in Fig. 2 and the pins 26 and 27 project through 55 the openings 20 and 22, assuming the dotted positions. In order to completely lock fish-plates 7 and 8, fish-plate 8 is now caused to slide on base-plate 4 and in so doing, pins 23 and 25 fill in the recesses 26 and 27 60 and pins 18 and 19 follow their respective

slots 14 and 15. The rail joint is now completed by this movement of fish-plate 8. In order to hold the plates together, a spike 29 or some suitable fastening means is inserted at 29^a which is an opening in fish-plate 8. 70 This spike then holds the fish-plate 8 in a permanent position preventing any sliding unlocking movement and as a result, a very simple and durable joint is obtained.

What I claim is:

1. In a rail-joint composed of two abutting sections of standard T-rail, the webs of each of said sections of rail having openings therethrough and having a slot in the under surface of the rail-head of each section of rail and on both sides of the webs of said rails, the combination with said rail-sections of a primary fish-plate and a secondary or sliding fish-plate, said primary fish-plate resting against one side of each 80 of said rail-sections and having on its side adjacent the face of the rail-web a horizontal L-shaped locking pin projecting therefrom and adapted to pass through one of the openings in one of said rail-webs and 85 engage an L-shaped recess in the secondary fish-plate on the opposite side of said rail-webs, said primary fish-plate having on its upper face two projecting locking pins each 90 of which is adapted to engage the respective slot in the under surface of the rail head, said secondary fish-plate having horizontal L-shaped locking pins projecting therefrom and adapted to pass through the respective openings in said rail-webs and 95 engage L-shaped recesses in the primary fish-plate on the opposite sides of said rail-webs, said secondary fish-plate having on its upper face two projecting locking-pins 100 each of which is adapted to engage the respective L-shaped slot in the under surface of the rail-head, the several L-shaped locking pins and recesses and locking pins and 105 slots of the above mentioned fish-plates being brought into locking engagement with 110 each other as the said secondary fish-plate is moved horizontally for locking the said rail sections together, and locking means 115 for preventing relative horizontal movement of the parts.

2. In a rail-joint composed of two abutting sections of standard T-rail, the webs of each of said sections of rail having openings therethrough and having a slot in the under surface of the rail head of each section of rail and on both sides of the webs of said rails, the combination with said rail-sections of a primary fish-plate and a secondary or sliding fish-plate, said primary fish-plate resting against one side of each 120 of said rail-sections and having on its side adjacent the face of the rail-web a horizontal L-shaped locking pin projecting therefrom and adapted to pass through one 125 of the openings in one of said rail-webs and 130

engage an L-shaped recess in the secondary fish-plate on the opposite side of said rail webs, said primary fish-plate having on its upper face two projecting locking pins each of which is adapted to engage the respective slot in the under surface of the rail-head, said secondary fish-plate having horizontal L-shaped locking pins projecting therefrom and adapted to pass through the respective 5 openings in said rail-webs and engage L-shaped recesses in the primary fish-plate on the opposite sides of said rail-webs, said secondary fish-plate having on its upper face two projecting locking-pins each of 10 which is adapted to engage the respective L-shaped slot in the under surface of the rail head, the several L-shaped locking pins and recesses and locking-pins and slots of the above mentioned fish-plates being 15 20 brought into locking engagement with each other as the said secondary fish-plate is moved horizontally for locking the said rail sections together, and locking means for preventing relative horizontal movement of 25 the parts, and a tie-plate mounting embracing the lower portion of said rail and both fish-plates, including a base plate, a pair of solid block members on said base plate extending upward therefrom and having their 30 inner and opposite faces inclined toward each other and engaging the outer lateral faces of said fish-plates.

3. A fish-plate having a horizontal L-shaped locking pin projecting from the side 35 of said fish-plate adjacent the face of the web of a standard T-rail, a projecting locking pin on the upper face of said fish plate and adapted to engage a rail end, and a second pin on the upper face of said fish-plate 40 and adapted to engage a second and abutting rail-end, and the main portion of said fish-plate having two horizontal L-shaped recesses formed therein, the openings of said recesses being on the same side of the plate 45 as the locking pin and said recesses extending within said plate in a direction opposite to the direction of the outer arm of the L-shaped locking pin.

4. A fish-plate having a horizontal L-shaped locking pin projecting from the side 50 of said fish-plate adjacent the face of the web of a standard T-rail, a projecting locking pin on the upper face of said fish plate and adapted to engage a rail end, and a second pin on the upper face of said fish plate 55 adapted to engage a second and abutting rail-end, and the main portion of said fish-plate having a horizontal L-shaped recess formed therein, the opening of said recess being on the same side of the plate as the locking pin, and said recess extending within said plate in a direction opposite to the direction of the outer arm of the horizontal L-shaped locking pin.

5. A fish-plate having a plurality of horizontal L-shaped locking pins projecting from the side of said fish plate adjacent the face of the web of a standard T-rail and facing in the same direction, a projecting locking pin on the upper face of said fish plate 70 and adapted to engage a rail end, and a second pin on the upper face of said fish plate and adapted to engage a second and abutting rail end, and the main portion of said fish-plate having a horizontal L-shaped recess formed therein, the opening of said recess being on the same side of the plate as the locking pins, and said recess extending within said plate in a direction opposite to the direction of the outer arms of the horizontal L-shaped locking pins, the lower portion of said fish-plate on the side opposite to the L-shaped member being cut away from top to bottom for the reception of a locking member.

6. In a rail joint composed of two abutting sections of standard T-rail, the web of one of said sections of rail having two openings therethrough, adapted to permit locking pins of corresponding dimensions to pass therethrough, the under surface of the head of the rail on one side of the web having a slot therein extending from the longitudinal edge to the web of said rail, the bottom of said slot being parallel with the top of the rail head, and the under surface of the head of the rail on the corresponding opposite side of the web having an L-shaped slot therein, one end of said slot being adjacent the longitudinal edge of said rail 95 head and the other end of said slot extending toward the end of said rail section, the bottom of said L-shaped slot being parallel with the top of the rail head.

7. In a rail joint composed of two abutting sections of standard T-rail, the web of one of said sections of rail having an opening therethrough, said opening being adapted to permit a locking pin of corresponding dimensions to pass therethrough, the under surface of the head of the rail on one side of the web having a slot therein extending from the longitudinal edge to the web of said rail, the bottom of said slot being parallel with the top of the said head and the under surface of the head of the rail on the corresponding opposite site of the web having an L-shaped slot therein, one end of said slot being adjacent the longitudinal edge of said rail head and the other end of said slot extending away from the end of said rail section, the bottom of said L-shaped slot being parallel with the top of the rail head.

8. In a rail joint composed of two abutting sections of standard T-rail, the webs of each of said sections of rail having openings therethrough and having a slot in the under surface of the rail head of each section of rail and on the same side of the webs of said rail 125 and on the same side of the webs of said rail 130

rails, the combination with said rail sections of a fish-plate resting against one side of each of said rail sections, said fish-plate having on the side thereof adjacent the face of 5 the rail web, a horizontal L-shaped locking pin projecting therefrom and adapted to pass through one of the openings in one of said rail webs and engage an L-shaped recess in a supporting engaging member on 10 the opposite side of said rail webs, said fish-plate having on its upper face two projecting locking pins each of which is adapted to engage the respective slot in the under surface of the rail head whereby said rail 15 sections are held together.

9. In a rail joint composed of two abutting sections of standard T-rail, the webs of each of said sections of rail having openings therethrough and having a slot in the under 20 surface of the rail head of each section of

25 rail and on the same side of the webs of said rails, the combination with said rail sections of a horizontally sliding fish-plate resting against one side of each of said rail sections, said fish-plate having on the side thereof adjacent the face of the rail web two horizontal L-shaped locking pins projecting therefrom and adapted to pass through the 30 openings in said rail webs and engage L-shaped recesses in a supporting engaging member on the opposite sides of said rail webs, said fish-plate having on its upper face two projecting locking pins each of which is adapted to engage the respective L-shaped slot in the under surface of the rail head 35 as said fish-plate is moved horizontally with respect to said rails and engaging member.

In testimony whereof I affix my signature.

WINCENTY WORONIECKI.
